(57) **CLAIM**

The ornamental design for an shelf assembly set with rail controller and electronic shelf labels as shown and described.

DESCRIPTION

FIG. 1 is a rear perspective view of the shelf assembly set with rail controller and electronic shelf labels;
FIG. 2 is a front perspective view thereof;
FIG. 3 is a rear side elevational view thereof;
FIG. 4 is a front side elevational view thereof;
FIG. 5 is a left side elevational view thereof;
FIG. 6 is a right side elevational view thereof;
FIG. 7 is a bottom plan view thereof; and,
FIG. 8 is a top plan view thereof.

The broken line portion of the figure drawings is included to show portion of the article that form no part of the claimed design.

1 Claim, 5 Drawing Sheets
